UNITED STATES PATENT OFFICE.

WILLIAM R. FILES, OF PROVIDENCE, RHODE ISLAND.

DRYING-MACHINE.

1,175,736.

Specification of Letters Patent. Patented Mar. 14, 1916.

Application filed October 4, 1915. Serial No. 53,900.

To all whom it may concern:

Be it known that I, WILLIAM R. FILES, a citizen of the United States, and resident of the city of Providence, in the county of Providence and State of Rhode Island, have invented certain new and useful Improvements in Drying-Machines, of which the following is a specification.

This invention relates to drying machines 10 of the class having a plurality of steam heated cylinders arranged to dry long strips of cloth, paper, yarn or other material, upon being run therethrough and the same is an improvement on my prior Patent No. 15 1109977.

The object of my present invention is to provide an improved construction whereby the low pressure or exhaust steam may be used with greater efficiency and economy for 20 drying goods, the same comprising a plurality of rotatable drying cans into which steam is admitted, the exhaust from said cans being passed through a water seal, where the air and steam vapor are separated 25 from the liquid to pass into a relief main, and the liquid portion is discharged into a main exhaust, also to provide one or more modifying cylinders, into which the contents of the relief main, also a second vapor portion, subsequently separated from the contents of the exhaust main, are caused to discharge, for the purpose of heating this cylinder with that which would otherwise be wasted.

30 The invention further consists in the provision of an equalizing pipe connecting the exhaust and relief mains, for equalizing the pressures in both, to prevent the seals at the ends of the cylinders from blowing out or 40 becoming emptied.

The invention further consists in the provision of a separator in the exhaust main line, and the connecting of a vaporizing chamber to said separator for the purpose of 45 permitting the vapor to again separate from the liquid which second separation is due to the escape of the latent heat, as the pressure in this main is now reduced after passing through the trap to that of the atmosphere and this vapor thus permitted to separate, is raised by a jet from the relief main 50 passing through the injector, whereby the

heated vapor from both is forced into the modulating can heating the same by that which would otherwise be wasted.

A further object of the invention is to provide a water seal between the vaporizer and the discharge outlet, for the purpose of holding back or preventing the heat or the heated vapors in the vaporizer from escaping too readily therefrom, whereby it is made possible to utilize the vapor in the vaporizer to assist in heating the modifying can.

With these and other objects in view, the invention consists of certain novel features of construction, as will be more fully described, and particularly pointed out in the appended claims.

In the accompanying drawings: Figure 70 1— is a side elevation showing a portion of my improved drying machine and illustrating the exhaust side of the piping system. Fig. 2— is a sectional view through the ends of one of the drying cylinders and its bearings, also showing one of the seals in section. Fig. 3— is a diagrammatic view illustrating the operation of the fluid in the system. Fig. 4— is an enlarged side elevation 75 illustrating the injector feature of the system.

Referring to the drawings, 10 and 11 designate two horizontal rails, forming the framework of the machine. They are preferably made hollow and some may serve as 80 conduits to receive either the supply or the exhaust steam when desired. These beams may be spaced apart and supported by the uprights 12. Mounted on these frames in suitable bearings are two rows of cylinders 85 13 and 14, each cylinder being provided with suitable intermeshing gears 15 and 16 through which they are driven in unison from the main shaft 17 and pinion 18. These cylinders are hollow and are each 90 provided with a hollow trunnion 19, see Fig. 2, through which the steam enters from the main 20 through pipe 21, hollow frame 10, and channel 11, and after heating the cylinder a portion of the steam is condensed, and the water of condensation rises through the downwardly turned pipe 23 and passes through trunnion 22 and channel 24, into the water seal 25. Here it enters the chamber

26 where it is forced against the baffle plate
 27 and here caused to separate, the comparatively dry steam, air and vapor passing upward through pipe 28 into the relief main
 29, while the water of condensation passes downward through the drop leg 30 to enter the exhaust main 31. In order to equalize the pressures in the relief main 29 and the exhaust main 31, I have connected them together by an equalizing pipe 32, whereby the pressures in both are equalized to prevent the water being blown or emptied from the seals regardless of different pressures which may be carried by the system.

15 A feature of my present invention is my improved means for further utilizing the latent heat in the discharge from the main cylinders for heating the modulating cylinder 42. This is accomplished by inserting a separator 33, see Fig. 3, into the main line exhaust, from the top of which the separated vapor is discharged approximately at atmospheric pressure and conducted through the pipe 34 into the vaporizing chamber 35. From this chamber is connected a drop leg 36, a horizontal extending portion 37, and a short riser 38 all of which serve to form a water seal, and so control the flow through the discharge pipe 39. By this construction and arrangement it will be seen that owing to the fact that the pressure has been considerably reduced by passing through the trap or separator, the latent heat is at once liberated, permitting the vapor to rise therefrom, and separate from the liquid. Leading from this vaporizer is a riser pipe 40, communicating with the trunnion 41 of the modulating cylinder 42 and in order to create a draft to lift this separated vapor from the vaporizer and discharge the same into the modulating can, I have provided an injector 43 which is connected to the drop leg 29^a of the relief main 29, the pressure from which is caused to pass through the nozzle 43 of the injector and create a vacuum in the portion 44 of the trunnion, and so lift this vapor from the vaporizer and discharge the same into the modulating can. As fast as the steam condenses to a certain predetermined height in this modulating can it is lifted to the trunnion 45 by the usual discharge pipe at the opposite end, and discharged through the drip pipe 46 into the funnel 47 whence it runs down and passes out through the main discharge 39.

60 By my improved construction it will be seen that the modulating cylinders are heated entirely by steam which has once been used in the other cylinders and which by my improved system is utilized to the greatest advantage in producing just the exact amount of heat desired in this so called modulating cylinder and this heat

may be nicely controlled by closing or opening the valve 48. By thus being able to regulate the heat in the entering end of the machine, the disagreeable feature commonly known as blistering, on dye goods 70 or the like, is effectually prevented.

I claim:

1. A drying machine comprising a plurality of rotatable drying cans, a steam inlet to said cans, an exhaust main receiving the liquid discharge from said cans, a relief main receiving the air and vapor from said cans, an equalizing pipe between said exhaust and relief mains, a modulating can, and means whereby the contents 80 of said relief main and a portion of the contents of said exhaust main are caused to discharge into said modulating can.

2. A drying machine comprising a plurality of rotatable drying cans, a steam inlet to said cans, an exhaust main receiving the liquid discharge from said cans, a relief main receiving the air and vapor discharge from said cans, a modulating can, and an ejector through which the contents of the relief main passes to drive the vapor from said exhaust main into said can.

3. A drying machine comprising a plurality of rotatable drying cans, a steam inlet to said cans, a relief main receiving the air and vapor discharge from said cans, an exhaust main receiving the liquid discharge from said cans, a separator in said exhaust main line, a vaporizer connected to said separator and means whereby the contents of said relief main and a portion of the contents of said vaporizer is caused to enter and heat said modifying can.

4. A drying machine comprising a plurality of rotatable drying cans, a steam inlet to said cans, a relief main receiving the air and vapor discharge from said cans, an exhaust main receiving the liquid discharge from said cans, a separator in said exhaust main line, a vaporizer connected to said separator and an injector through which the contents of the relief main passes to force the vapor from said vaporizer into said can.

5. A drying machine comprising a plurality of rotatable drying cans, a steam inlet to said cans, a relief main receiving the air and vapor discharge from said cans, an exhaust main receiving the liquid discharge from said cans, a separator in said exhaust main line, a vaporizer connected to said separator, a water seal in the discharge from said vaporizer, an injector through which the contents of said relief main passes, a riser pipe from said vaporizer to said injector through which the vapor is drawn therefrom and discharged into said modulating can.

6. A drying machine comprising a plurality of rotatable drying cans, a steam inlet to said cans, an exhaust main receiving the liquid discharge from said cans, a relief main receiving the air and vapor discharge from said cans, a pressure equalizing pipe between said exhaust and relief mains, a modulating can, and an injector through which the contents of the relief main passes to drive the vapor from said 10 exhaust main into said modulating can.
- In testimony whereof I affix my signature in presence of two witnesses.
